UNITED STATES PATENT OFFICE.

NEWTON S. HILLYARD, OF ST. JOSEPH, MISSOURI.

DUST MOP.

Application filed July 3, 1925. Serial No. 41,426.

This invention relates to floor mops and particularly to dust mops, the primary object being to provide an efficient mop head with a liquid distributor to cause liquid to flow uniformly over the mop cloth to impregnate the mop fabric whereby the mop cloth will be moistened with the liquid.

The liquid will consist of a floor dressing or composition to take up the dust and renew the finish of the floor. The particular liquid employed will be immaterial in so far as this invention is concerned, the invention residing more particularly in the mop head construction, the novel features of which will be apparent by reference to the following description in connection with the accompanying drawings, in which—

Fig. 1 is a perspective view of a completed mop constructed in accordance with my invention.

Fig. 2 is a cross sectional view through the same, and

Fig. 3 is a disassociated view of the parts of the mop head, the mop fabric also being shown detached from the head.

The mop head is shown as comprising two main members 1 and 2 with a handle and means for securing the handle to one of the members, the two members being so co-related that they may clamp the mop fabric 4 between them. The handle 3 is secured to the member 1 by a novel construction which will be described hereinafter. The member 1 is shown as comprising a pan formed by bending the longitudinal edges of the member 1 upwardly to provide flanges 5 and 6, the upstanding end flanges 7 and 8 also being integral with the main body portion of the pan, the end flanges being held in place by overlapping ends 9 on the side flanges 5 and 6. The side flanges are provided with openings 10 at the perimeter of the pan so that when liquid is poured into the pan it may be distributed onto the mop fabric 4 through the openings, and since the openings are arranged along the entire length of the pan it is obvious that liquid will be uniformly distributed throughout the length of the mop fabric on both sides of the pan so that there will be a uniform impregnation of the cords of the mop fabric.

In order to secure the mop fabric to the pan 1 I provide means for securing the member 2 to the member 1 in clamping position.

It will be observed that the mop fabric is formed of cords held together by a tape 11

in the form of a band stitched to the cords and that the tape is provided with an opening 12, the purpose of which will presently be apparent.

The member 2 is provided with upstanding longitudinal flanges 13 and 14 and on the end of the member 2 are two upstanding arms 15 and 16, the hooked ends 17 and 18 of which are adapted to engage the upper edge 65 of the flange 8. In the body portion of the member 2 is an upstanding latch-receiving finger 19 having a right angular end 20. The material for forming the finger 19 and the end 20 may be struck up from the material of the member 2, as will be clearly seen by reference to Fig. 3. The finger 19 with its end 20 is adapted to pass through the opening 12 and through the opening 21 in the bottom of the pan or member 1. Secured 75 to the bottom of the pan is a hook-shaped latch 22 pivoted at 23 and having a lug 24 by means of which the latch can be swung about the axis of its pivot. The bottom of the pan is also provided with an up-struck 80 boss or projection 25 over which the latch may ride, the latch being provided with a concave portion 26 which will allow it to be guided up over the boss or projection 25 when the latch is moved into position to have its finger 27 slide under the projection 20 as shown in Fig. 1. The boss 25 tends to hold the latch in latched position. It will be understood that when the fabric is clamped between the members 1 and 2 the 90 mop is ready for use provided that the handle is appropriately secured to the member 1.

I have provided a novel fastening means for the handle which consists of a block 28 riveted or otherwise fastened to the member 1. The block has a transverse slot 29 and a longitudinal slot 30. Extending upwardly from the block 28 is a screw 31. The head of the screw may be received in the recess 32 in the block 28 and held against movement in one direction by the bottom of the member 1. The screw is of sufficient length to receive the handle and the fastening device. The block is provided with teeth or projections 33 and 34 for one slot 100 and teeth 35 and 36 for the other so that there will be teeth on the projections to engage the notches 37, 38, 39 and 40 on the head 41 of the handle 3. The head 41 is provided with an elongated slot 43 through which the threaded portion of the screw 31 projects, the elongated slot permitting the

head on the handle to be tilted to arrange the handle at a convenient angle, and after the adjustment has been made the handle can be secured tightly against the block by the wing nut 44 which bears against the washer 45 resting upon the upper face of the head 41, as clearly shown in Fig. 2. The handle may be arranged either longitudinally or transversely of the elongated member 1. Since the two slots in the upper face of the block are at right angles one to the other and since the angle of inclination of the handle may be varied, practically any adjustment required may be made by loosening the wing nut which holds the handle to the block.

If it is desired to remove the mop fabric for cleaning or for any other purpose it will be necessary only to swing back the hook-shaped latch in the position shown in Figure 3 so that the finger 19 and the projection 20 can be dropped out of the opening 21 whereupon the hooks 17 and 18 may be unhooked from the edge of the flange 8.

The mop head may be constructed inexpensively, it may be easily put together and taken apart and in actual use it will be practically indestructible, and a very important feature of the invention is the uniform or equal distribution of the liquid from the pan to the mop cloth.

What I claim and desire to secure by Letters Patent is:—

1. A mop head, comprising a liquid-receiving pan having liquid outlet orifices at its perimeter, a plate detachably hinged thereto, and means connecting the pan and the plate so that they may clamp a mop fabric between them.

2. A mop head, comprising a liquid distributor consisting of a plate having an upstanding edge wall provided with open-

ings, a mop fabric clamping plate between which and the liquid distributor the mop fabric may be clamped, means on one member projecting through the other member, and a latch on said other member for engaging said means to removably clamp said plates together.

3. A mop head, comprising a liquid-receiving pan having openings in its side edges and an opening in its bottom, a latch on the bottom having movement over the opening, and a member co-operating with the pan to clamp a mop fabric to the pan, said member comprising a plate, hooks on the plate to engage the pan, a finger on the plate to pass through the mop fabric and through the opening in the bottom of the pan, and a latch carried by the pan to engage the opening.

4. A mop, comprising two clamping members and a mop fabric between them, one member comprising a liquid-receiving pan having openings to distribute liquid to the mop fabric, a latch on the pan movable over an opening in the bottom of the pan, and handle-receiving means on the pan, the other member comprising a plate having a finger projecting through said opening in the pan and engageable by the latch.

5. A mop, comprising two clamping members and a mop fabric between them, one member comprising a liquid-receiving pan having openings to distribute liquid to the mop fabric, the pan having an opening in its bottom and a latch movable over the opening, the other member having means at one end to engage the pan and a finger projectible through the fabric and through the pan engageable by the latch.

In testimony whereof I affix my signature.

NEWTON S. HILLYARD.
